UNITED STATES PATENT OFFICE.

ELI P. WILLIAMS, OF MCPHERSON, KANSAS.

FOLDING-BOX BLANK.

Application filed May 17, 1926. Serial No. 109,456.

My invention relates to improvements in folding box blanks. It relates particularly to foldable blanks for making paper boxes, of the type having side and end members, adjacent ones of which overlap and are fastened together by a tongue on one member provided with a head which is inserted through a slit in the other member for locking engagement therewith.

10 One of the objects of my invention is to provide a novel blank of the kind described, which is simple, cheap, quickly and readily assembled to form a box in which the head of the tongue is overlapped on its inner and outer 15 sides by the member through which it is extended, whereby the head is firmly held flatwise against the adjacent member.

A further object of my invention is to provide a novel form of slit which enables the head of the tongue to be easily inserted therethrough and by which the head forms a lock with the member having the slit with which the members are held securely together and are not liable to accidental detachment from 25 each other in handling or shipping.

My invention provides further a box blank having a member provided with a transverse slit through which the locking head of an adjacent member is insertable, the head engaging the ends of the slit and projecting beyond the ends thereof.

The invention provides further a novel lock, which is strong, not easily torn and which affords smooth inner and outer surfaces without loose free flaps liable to interfere with the application of a cover to the box.

The novel features of my invention are hereinafter fully described and claimed.

In the accompanying drawing, which illustrates the preferred embodiment of my invention and a modification thereof,

Fig. 1 is a perspective view of a box formed from one of my improved box blanks.

Fig. 2 is a side elevation of a corner portion of the box, the tongue of the end member shown being shown disengaged from locked engagement with the adjacent side member.

Fig. 3 is a top view of one corner of the box.

Fig. 4 is a plan view of the unfolded blank.

Similar reference characters designate similar parts in the different views.

1 Designates the portion of the blank which is to form the bottom of the box, or the top of the cover, when the box is used as a cover for a box.

2 Designates end members foldably at-

tached to opposite ends respectively of the bottom portion 1, each end of each end member 2 having a foldable tongue 3 having a neck 4 and a head 5 which projects laterally at opposite edges of the neck.

6 Designates two side members having foldable connection with the bottom portion 1, and provided each adjacent to its respective ends with two slits, each of which is unbifurcated and has a transverse portion 7, which, preferably, inclines from the bottom portion 1 and adjacent end of the member 6 toward the distant end of said member, and which at the end distant from the bottom portion 1 joins a portion 8 of the slit.

The portion 8 of each slit extends from a point 9, spaced from the adjacent end of the member 6, toward the distant end of said member, and in the form shown in Figs. 1 to 4 is joined by the portion 7 at the end of the portion 8 which is nearest the distant end of the member 6.

The portions 7 and 8 of each slit preferably form an acute angle and a lip 10.

In forming the box from the blank, the side members 6 and the end members 2 are folded in the usual manner to the upright positions, the heads 5 being inserted respectively from the outer sides of the side members 6 over the lips 10 and through the slits until the heads are disposed almost wholly within the box, after which the end members 2 are pulled outwardly until the head 5 and opposite edges of the neck 4 of each end member lockingly engage the member 6 adjacent thereto at the ends of the slit through which the head is inserted. The heads 5 will now be overlapped on their inner sides respectively by the lips 10, Fig. 1, whereby the heads are held clamped flatwise at their inner and outer sides by the members 6, so that, as the slit has no branches but is unbroken throughout, there are no loose free flaps that will project laterally inwardly or outwardly to interfere with the application of a cover, or which are liable to catch on adjacent things with liability of tearing, or unlocking of the side and end members from each other.

The distance between the ends of each slit is approximately the width of the adjacent neck, and, as the head 5 projects above and below the ends of the transverse portion 7 of the slit, a secure lock is effected, see Fig. 1.

As the end member 2, in forming the box, swings with the adjacent end of the bottom 1 as an axis, and as the portion 7 of the slit in-

clines from the bottom and toward the distant end of the side member 6, and forms an acute angle with the portion 8 of the slit, and as the radial distance from said axis to the 5 most distant point on the periphery of the head 5 is substantially the same as the distance from said axis to the apex of the lip 10, that is the point where the portions 7 and 8 of the slit join, as shown in Figs. 2 and 4, the 10 head 5 is easily inserted and then withdrawn to the locked position, without having to bend or distort the head. In order that this may be effected, the ends of the slit are respectively approximately the same distances from 15 the axis of the member 2 as are the points of joinder of the head with the opposite edges of the neck.

By having the portion 7 of the slit intersect the portion 8 thereof at a point spaced from 20 the point 9, Figs. 1 to 4, there are no free flap portions formed by the slit at the outer side of the side member 6, after the head is inserted, as would occur in constructions in which the transverse portion joins the longitudinal portion of the slit at the end thereof nearest the 25 adjacent end member.

I do not limit my invention to the structures shown and described, as other modifica-

tions, within the scope of the appended claim, may be made without departing from the 30 spirit of my invention.

What I claim is:—

A box blank having a bottom and two members having foldable connection therewith, one member having a tongue foldable over the other member and provided with a neck and a head which projects laterally from both edges of the neck, said other member having a slit the ends of which are respectively the same distances approximately from the axis 35 of the first named member as are the points of joinder of the head with the edges of the neck, said slit comprising two portions at an acute angle to each other and meeting at a point substantially the same distance from said axis 40 as is the most distant point on the periphery of said head, the distance between the ends of the slit being less than the width of said head at said points of joinder, whereby said head is adapted for insertion, without bending, 45 through said slit and to lock with said other member at both ends of said slit. 50

In testimony whereof I have signed my name to this specification.

ELI P. WILLIAMS.
